IMPROVEMENT IN CHURNS.

ANDREW J. VANATTA, OF VANATTA, OHIO.

Letters Patent No. 60,289, dated December 4, 1866.

SPECIFICATION.

TO ALL WHOM IT MAY CONCERN:

Be it known that I, ANDREW J. VANATTA, of Vanatta, in the county of Licking, and State of Ohio, have invented a new and Improved Churn; and I do hereby declare that the following is a full, clear, and exact description thereof, reference being had to the accompanying drawings forming part of this specification.

The nature of my invention consists in so constructing and combining a spur-wheel and pinion as to give to the dasher of a churn both a rotary and vertical motion, for the purpose of breaking the rotary current of the cream made by the rotary dashers, and at the same time agitate the inert cream around the centre of the churn, by having independent motions, both to the rotary and vertical moving dashers.

To enable others skilled in the art to make and use my invention, I will proceed to describe its construction and operation.

Figure 1 is a longitudinal vertical sectional elevation of my improved churn.

Figure 2 is a side elevation of the same.

Figure 3 is a transverse section from the line $z z$; showing the plan of the dashers.

Letters of like name and kind refer to like parts in each of the figures.

A represents the cylinder or barrel of my improved churn, which is of common form and construction, upon the top of which is a cover, B, that is made in two sections, the said sections being hinged together at a , fig. 2. This cover is secured to the barrel or cylinder of the churn by means of hooks, $e e e$, and eyes or pins, $i i i$. The said hooks, e being secured to the barrel of the churn by pivot screws, $n n n$, and the eyes or pins, $i i i$, are secured to the lid or cover, B, by any well known means. Upon the cover, B is erected and secured a suitable frame represented by C. To this frame, C, is attached the gears that drive the churn. D is a gear-wheel that is provided with a shaft, E, which runs in a bearing, F, that is secured to and extends out from the frame, C, upon the end of which is the crank, G, by which the churn is operated. This gear-wheel, D, fits and meshes into a corresponding pinion-wheel, H, which is also provided with a shaft, I, that runs in a bearing, J, which is also secured to the frame, C. Upon the end of the said shaft, J, and joining the pinion-wheel, H, is a crank-wheel, K, on the side of which is a crank pin, u , to which is connected the upper end of the pitman, L, the lower end of the said pitman being connected to the upper end of the dash rod, M, by the pivot bolt, S. This dash rod extends down into the cylinder of the churn and is attached to the dash or beater, N. This dash or beater, N, is attached to the rotary beaters, O, (which will be hereinafter explained,) by means of gibbs, the said beaters serving the purpose of ways or guides for the dash or beater, N. P is a beveled gear-wheel located and secured upon the side of the rim of the gear-wheel, D, the said beveled wheel, P, meshes into a corresponding bevel pinion, Q, that is secured to and runs in the hollow shaft, R, the lower end of which is secured to the cross-piece, S, of the rotary dash, O. T is a pointed gudgeon, firmly secured to the lower cross-bar, U, of the rotary dash or beater, O. This said gudgeon runs in a bearing, V, that is firmly fastened in the centre of the bottom of the cylinder or barrel, A. Now, it will be observed that the beater, N, has a vertical rotating motion, while the beater, O, has only a rotary motion. The beater, N, rotates upon the bearing at V, upon the dash-rod, M, receiving its rotary motion from the beaters, O.

The operation of my improved churn is easy, rapid, and perfect. By introducing the milk or cream into the churn, then by turning the crank, G, motion is imparted to the beaters, O and N, through the medium of the gear-wheels, H D and P Q. The gear-wheels, H D, operating the beater, N, vertically, at the same time the wheels, P and Q, impart a rotary motion to the beater, O, also to the beater, N, so that the inert milk or cream in the centre of the churn is agitated, and the rotary current of the cream produced by the beaters broken and a uniform agitation is created throughout the whole body of cream.

Having thus described my invention, what I claim as new and desire to secure by Letters Patent, is—

1. The combination of the wheel D, and wheel P, with the pinions H and Q, for the purpose of giving the beaters N, both a vertical and rotary motion at the same time, so as to break the rotary current of the cream at the sides of the churn, substantially, as shown and described.
2. I claim the dasher N, having a bearing V, on the rod M, so as to have a rotary motion, at the same time a vertical motion, substantially as shown and described.
3. The beater O, in combination with beater N, substantially and for the purpose described.
